MOUNTING FOR A HAND TELEPHONE

Henry Dreyfuss, Pasadena, Calif., assignor to Bell Telephone Laboratories, Incorporated, New York, N. Y., a corporation of New York

Application March 15, 1949, Serial No. 1,409

Term of patent 14 years

(Cl. D26—14)

To all whom it may concern:

Be it known that I, Henry Dreyfuss, a citizen of the United States, residing at Pasadena, in the county of Los Angeles, and State of California, have invented a new, original, and ornamental Design for a Mounting for a Hand Telephone, of which the following is a specification, reference being had to the accompanying drawing, forming a part thereof.

Fig. 1 is a front elevational view of the mounting for a hand telephone, showing my new design;

Fig. 2 is a side view of the mounting, taken from the right in Fig. 1; and

Figs. 3 and 4 are top and bottom views respectively of the mounting.

I claim:

The ornamental design for a mounting for a hand telephone, as shown.

HENRY DREYFUSS.
